HYDRAULIC BRAKE SYSTEM

Herbert C. Bowen, Detroit, Mich., assignor to
 Hydraulic Brake Company, Detroit, Mich., a
 corporation of California

Application September 16, 1933, Serial No. 689,715
 Renewed June 15, 1939

14 Claims. (Cl. 60—54.6)

This invention relates to hydraulic brake systems, and more particularly to fluid pressure devices therefor.

Heretofore in fluid brake systems having pressure devices operable through a foot pedal lever, the ratio of pedal movement to fluid flow changes at a predetermined point in the pedal movement to produce a greater fluid pressure without proportionately greater foot pressure. The transition takes place suddenly, with the result that there is a period immediately following, which is uncontrollable on the part of the operator. For example, assume that a pressure of sufficient value at the point of transition to effect a deceleration of five feet per second per second, the pressure in this instance being compounded to effect a deceleration of ten feet per second per second. From this it will be readily seen that no stops can be effected between five and ten feet per second per second. The present invention aims to overcome this objection.

An object of the invention is to spread the transition from low to high pressure over a prolonged period to smooth out the operation of the system.

Another object of the invention is to provide a fluid pressure device wherein simultaneously operable low and high pressure producing means are provided.

Another object of the invention is to provide means controlled by pressure in the system for effecting gradual transition from a low to a high pressure.

A further object of the invention is to provide means controlled by pressure in the system for dis-associating the low pressure producing means from the system.

An additional object is to provide a device of the character herein described which is simple and inexpensive in structure, highly efficient in use, positive in action, durable in service, and a general improvement in the art.

Other objects and advantages of the invention will appear from the following description taken in connection with the drawing forming a part of this specification, and in which—

Figure 1 is a vertical sectional view of a reservoir and a compound cylinder embodying the invention, and

Figure 2 is a schematic illustration of a complete hydraulic brake installation including the reservoir and cylinder.

Referring to the drawing for more specific details of the invention, 10 represents the frame of a motor vehicle chassis. The frame has suitably secured thereto a housing 12 including a reservoir

14 having an open top and a drain opening 16, the drain opening being closed as by a plug 18, and the top having fitted thereon a cover plate 20 provided with a filling opening 22 closed as by a plug 24 having a vent 26.

An operating shaft 28 extending transversely through the reservoir has suitably secured thereto, outside of the reservoir, a foot pedal lever 30 connected by a return spring 32 to a fixed support. The shaft 28 also has secured thereto, within the reservoir, a lever 34 having a lateral end 36 serving to transfer motion of the shaft 28 to a piston 38 operable within a cylinder 40.

The cylinder 40 is suitably supported on the wall of the reservoir adjacent the bottom thereof with its open end extending into the reservoir. The closed end or head of the cylinder projects from the wall of the reservoir, and is provided with an axial port 42, communicating with outlets 44, 46, and 48, respectively. The outlet 44 communicates with a pressure switch 50 connected in a circuit 52 including a battery 54 and a lamp 56, the circuit being grounded as indicated at 58. The lamp 56 is a conventional stop light such as is in general use. The outlets 46 and 48 are connected by fluid pressure delivery pipes or conduits 60 and 62 and branch pressure delivery pipes to motor cylinders 64 connected between the separable ends of friction elements 66 for spreading these elements into engagement with the drums 68 of wheel brakes 70, and the friction elements of the respective brakes are connected by retractable springs 72.

As shown, the cylinder 40 has a double diametral bore, providing a large and a small chamber. The larger chamber has a slot 74 for the reception of the actuating lever 34, and a port 76 providing a communication between the larger chamber and the reservoir, and a by-pass 78 provides a communication between the large and small chambers. The piston 38 reciprocable in the cylinder 40 includes a shell 80 fitted snugly in the larger chamber of the cylinder. This shell provides a chamber 82 having in its wall a plurality of ports 84 providing communications between the chamber and a circumferential chamber 86 communicating with a plurality of spaced openings 88 in a piston head 90 fitted in the larger chamber of the cylinder and having fitted thereon a collapsible leak-proof cup 92. The head 90 also has a passage 94 providing a communication between the chamber 82 and the larger chamber of the cylinder.

The head 90 has formed concentrically therewith a sleeve 96 of smaller diameter than the di-

ameter of the small chamber of the cylinder. This sleeve has a head 98 fitted snugly in the small chamber of the cylinder. The head 98 has a plurality of spaced openings 100 providing communications between the small chamber of the cylinder and the larger chamber of the cylinder, and positioned on the head 98 is a collapsible leak-proof cup 102 having an opening 104 registering with the bore of the sleeve 96. The cup 102 is held against displacement by a coil spring 106 interposed between the cup and a valve 108 for control of the port 42. The valve 108 has normally closed passages 109. The spring 106 also serves to return the piston to its retracted 15 position.

The sleeve has therein a reciprocable plunger 110 having thereon a leak-proof cup 112. The plunger has a head exposed to the fluid pressure in the smaller or high-pressure chamber and an annular portion 115 exposed to the fluid pressure in the larger or low-pressure chamber. The area of the plunger head is approximately two-thirds that of the annular portion 115. This plunger 110 also carries a disk valve 114 arranged to seat on a rubber gasket 116 in the chamber 82 to control the passage 94. The valve 114 is normally held against its seat by a coil spring 118 interposed between the valve and a spider 120 threaded in the shell 80. The spider 30 has thereon a sleeve 122 arranged concentrically with respect to the piston and the sleeve has therein a pressure plug 124 for the reception of the force applying end 36 of the lever 34.

Assuming that the system is filled with suitable liquid or fluid, upon depressing the foot pedal lever 30 the shaft 28 is moved through an angle, and this movement of the shaft is transferred through the lever 34 on the shaft to the piston 38 to move the piston into the cylinder 40. During the initial movement of the piston, pressure is received by the cup 92 on the head of the piston 90, and the fluid in the larger chamber of the cylinder is displaced through the head 98, past the cup 102 thereon into the smaller 45 chamber of the cylinder, and from thence through the valve 108, which prevents retrograde movement of the fluid, and through the port 42 and outlets 44, 46 and 48 communicating therewith.

50 Movement of the fluid under pressure through the outlet 44 actuates the pressure switch 50 to close the circuit 52 resulting in lighting the signal lamp 56, and simultaneously therewith the fluid moves under pressure through the outlets 55 46 and 48 and the delivery pipes or conduits 60 and 62 connecting these outlets to the motor cylinders 64, resulting in actuation of these cylinders to spread the brake elements 66 against the resistance of the retractor spring 72 into 60 engagement with the drums 68 of the brakes 70.

When the fluid in the cylinder is placed under a pressure which, when multiplied by the area of the head of the plunger 110 and the area of the valve 114, is slightly in excess of the load 65 on the compression spring 118, the plunger 110 is moved to trip the valve 114 and thereby relieve the fluid pressure in the larger chamber of the cylinder, a portion of the fluid being returned from the larger chamber of the cylinder through the passage 94, the valve 114, the chamber 82, and the spider 120 to the reservoir. 70

As the valve 114 opens the cup 102 seals against its cylinder wall and closes communication between the high-pressure chamber and the low-pressure chamber. The function of main-

taining pressure on the fluid in the small chamber is thus assumed by the piston head 98 and plunger 110 without appreciable loss of pressure in the high-pressure chamber and that part of the braking system connected therewith. 5

It is to be noted that the plunger 110 has a head exposed to the pressure in the high-pressure chamber and an annular portion 115 of larger area than the head of the plunger which is exposed to the pressure in the low-pressure chamber. The forces exerted on these two areas by the fluid pressures in the high and low-pressure chambers act in the same direction to crack the valve 114 against the tension of the compression spring 118. If the piston is being advanced slowly the cracking of this valve will lower the pressure in the low-pressure chamber to a greater extent than is immediately compensated for by the advance of the high-pressure head 98, with the result that the valve 114 again closes 20 and thus continues to crack and close until the pressure in the high-pressure chamber is high enough to create sufficient force on the head of the plunger 110 to overcome the force of the compression spring 118 without any assistance 25 from the fluid in the low-pressure chamber. Thereafter this valve will remain open throughout the remainder of the advance of the piston.

On the other hand, if the piston is being advanced with sufficient rapidity, the forward 30 movement of the high-pressure head 98 may immediately build up sufficient increase in pressure in the high-pressure chamber to compensate for the lowering of pressure in the low-pressure chamber due to the cracking of the 35 valve 114, whereupon this valve will continue to permit slow leakage there past as the pressure in the low-pressure chamber is gradually dissipated.

In both types of operation the object of the invention is accomplished in that the resistance 40 to the advance of the low-pressure head of the piston is gradually dissipated as the resistance to the advance of the high-pressure head increases and at no time is there any abrupt change in the total resistance offered by the piston to the 45 advancing movement of the foot pedal. The operator thus has full and complete control of the brakes at all times.

Upon release of the applied force on the foot 50 pedal lever 30, this lever is returned to its normal position by the spring 32. During this movement of the foot pedal lever, the piston 38 is moved to its retracted position by the return spring 106, and fluid is returned from the cylinders 64 under pressure of the retractor springs 55 72 connected between the friction elements 66 of the brakes 70.

Due to friction on the column of fluid in the cylinder 40 and the conduits connecting the cylinder 40 to the cylinders 64, and to the tension 60 of the spring 106, the piston returns to its retracted position slightly in advance of the return of the fluid to the cylinder 40. This causes a partial vacuum in the cylinder 40 resulting in collapse of the cups 92 and 102 and admission 65 of fluid from the reservoir to the cylinder.

Upon complete return of the piston to its retracted position, the by-pass 78 and the port 76 are uncovered, whereupon further pressure in the cylinder causes the cups to return to static 70 condition, and any excess fluid returned to the cylinder 40 from the cylinders 64 passes from the cylinder through the by-pass 78 to the larger chamber of the cylinder, and from thence through port 76 to the reservoir. 75

From the foregoing it will be readily understood that the range over which the transition of the pressure occurs may be determined entirely by the area of the head of the plunger 110, the range being greater when the area of the plunger head is small, and, of course, decreasing as the area of the plunger head increases.

Although this invention has been described in connection with certain specific embodiments, the principles involved are susceptible of numerous other applications that will readily occur to persons skilled in the art. The invention is, therefore, to be limited only as indicated by the scope of the appended claims.

15 I claim:

1. A fluid pressure mechanism of the class described, comprising a compound cylinder providing large and small bores, a supply reservoir communicating with said cylinder, a piston having a head in each bore, means for operating said piston to create fluid pressures in said bores, a passage through the larger head, said passage leading to said reservoir, valve means for said passage, said valve means having a separate area exposed to the fluid pressure in each bore, the forces exerted on said areas acting on said valve means in the same direction to open said valve and thereby gradually relieve the pressure in said larger bore, independent valve and passage means movable with the smaller head for controlling flow between said bores, means for replenishing said cylinder from said reservoir, and a spring for urging said first-named valve means to closed position.

35 2. A fluid pressure mechanism of the class described, comprising a compound cylinder providing large and small bores, a supply reservoir communicating with said cylinder, a piston having a head in each bore, means for operating said piston to create fluid pressures in said bores, a passage through the larger head, said passage leading to said reservoir, poppet valve means for said passage, said valve means having a separate area exposed to the fluid pressure in each bore, the forces exerted on said areas acting on said valve means in the same direction to open said valve and thereby gradually relieve the pressure in said larger bore, independent valve and passage means movable with the smaller head for controlling flow between said bores, means for replenishing said cylinder from said reservoir, and a spring for urging said first-named valve means to closed position.

55 3. A fluid pressure mechanism of the class described, comprising a compound cylinder providing large and small bores, a supply reservoir communicating with said cylinder, a piston having a head in each bore, means for operating said piston to create fluid pressures in said bores, a passage through the larger head, said passage leading to said reservoir, valve means for said passage, said valve means having a separate area exposed to the fluid pressure in each bore, said areas being of different sizes, the forces exerted on said areas acting on said valve means in the same direction to open said valve and thereby gradually relieve the pressure in said larger bore, independent valve and passage means movable with the smaller head for controlling flow between said bores, means for replenishing said cylinder from said reservoir, and a spring for urging said first-named valve means to closed position.

70 4. In fluid pressure mechanism of the class described, the combination of a compound cyl-

inder comprising large and small bores, a supply reservoir communicating with said cylinder, a piston in each bore, means for operating said pistons to create fluid pressures in said bores, a passage through the larger piston and connecting said reservoir with the larger bore, a plunger including a valve and an area exposed to the fluid pressure in each bore, the area exposed to the fluid pressure in the larger bore being larger than the area exposed to the fluid pressure in the smaller bore, the forces exerted on said areas acting in the same direction to open said valve and thereby reduce the pressure existing in the larger bore, means for refilling said cylinder from said reservoir, and a spring for urging said valve to closed position.

5 5. A fluid pressure mechanism of the class described, comprising a compound cylinder providing large and small bores, a supply reservoir communicating with said cylinder, a piston having a head in each bore, means for operating said piston to create fluid pressures in said bores, a passage through the larger head, said passage leading to said reservoir, valve means for said passage, said valve means having a separate area exposed to the fluid pressure in each bore, the area exposed to the fluid pressure in the smaller bore being approximately two-thirds of the size of the area exposed to the fluid pressure in the larger bore, the forces exerted on said areas acting on said valve means in the same direction to open said valve and thereby gradually relieve the pressure in said larger bore, independent valve and passage means movable with the smaller head for controlling flow between said bores, means for replenishing said cylinder from said reservoir, and a spring for urging said first-named valve means to closed position.

20 6. A fluid-pressure device comprising a reservoir, a cylinder having bores of different diameters, a piston having two heads of different diameters for creating fluid pressures in said bores, a sleeve connecting the heads, a plunger movable in said sleeve, said plunger being exposed to and urged in the same direction by fluid pressure in both of said bores, a passage through said piston head connecting the larger bore with said reservoir, a valve movable with said plunger to open and close said passage, and thereby control the pressure developed in said larger bore, and means whereby said cylinder is refilled from said reservoir.

25 7. A fluid-pressure device comprising a reservoir, a cylinder providing bores of different diameters, a piston including a shell providing a chamber, a piston head, a passage through said head communicating with the chamber, means connecting said chamber with said reservoir, a second head, said heads adapted to create fluid pressure in said bores, a sleeve connecting said heads, a plunger movable in the sleeve, a valve movable with the plunger for opening and closing said passage to control the pressure developed in said larger bore, said valve being urged toward open position by the fluid pressure existing in both of said bores, and a spring in the chamber urging the valve to its seat.

30 8. A fluid-pressure device comprising a reservoir, a two-diameter cylinder providing a pair of bores, a piston including a shell providing a chamber, a head on said shell, a passage through said head communicating with the chamber, means connecting said chamber with said reservoir, a second head, said head movable to create fluid pressure in said bores, a sleeve connecting

- said heads, a plunger movable in the sleeve and acted upon in the same direction by the pressures in said bores, a valve movable with the plunger for opening and closing said passage to control the pressure created in said larger bore, a spider in the shell, a spring interposed between the spider and the valve, and means for replenishing said cylinder from said reservoir.
9. A fluid-pressure device comprising a reservoir, a two-diameter cylinder providing a pair of bores, a piston including a cylindrical member having an axial bore, heads formed upon the ends of said cylindrical member, said heads adapted to create fluid pressures in said first-named bores and having openings registering with said axial bore, a skirt formed integral with one of the heads and providing a chamber, a plunger movable in said axial bore, a passage providing communication between the chamber and one of the bores, a valve movable with the plunger to open and close said passage and control the pressure in said last-mentioned bore, said plunger acted upon in the same direction by the pressures in both of said first-mentioned bores, a spider secured in the chamber and permitting communication between said chamber and said reservoir, a spring interposed between the spider and the valve, a pressure block supported by the spider, and means for refilling said cylinder from said reservoir.
10. A fluid pressure device comprising a cylinder having a double diametral bore providing two chambers, a piston reciprocable therein having spaced heads fitted in the respective chambers, and a bore extending through the respective heads, a skirt on one of the heads providing a housing, a plunger movable in said last-named bore, said plunger having a surface exposed to the fluid pressure in each chamber and being urged in the same direction by the action of the fluid pressures on both of said surfaces, a fluid reservoir, a passage connecting said reservoir with the larger of said chambers, a valve in said passage carried by said plunger, said valve controlling the release of pressure from said larger chamber, a member secured in said housing, a spring interposed between the member and valve, means for replenishing said cylinder from said reservoir, a second passage connecting said chambers, and a second valve independent of said first-mentioned valve for controlling said second passage.
11. A fluid pressure device comprising a reservoir, a cylinder supplied therefrom having a double diametral bore providing a low pressure chamber and a high pressure chamber, expansible elements connected to the high pressure chamber, brake elements actuated by the expansible elements, a valve controlling movement of fluid from the expansible elements to the high pressure chamber, a piston reciprocable in the cylinder having spaced heads fitted in the respective chambers and an axial bore extending through the heads, the smaller head having openings providing communications between the low and high pressure chambers, a collapsible cup on the smaller head controlling the opening, a skirt on the larger head providing a housing opening into the reservoir, the larger head having a plurality of openings providing communications between the low pressure chamber and the housing, a collapsible cup on the larger head

controlling the openings therein, a plunger movable in the bore, said plunger having a surface exposed to the fluid pressure in each chamber, said plunger being urged in the same direction by the action of the fluid pressures on both of said surfaces, a valve carried by the plunger, a passage providing a communication between the low pressure chamber and the housing, said valve controlling said passage, a support in the housing, a compression spring between the support and the valve, a block on the support, and an actuator engaging the block.

12. A fluid system for transmitting power between a foot pedal or like element and a brake cylinder and acting in several phases with different predetermined ratios of transmission, comprising a piston unit having a large piston and a small piston, means operated by the foot pedal for actuating the piston unit, a cylinder for each of said pistons, duct means between the small cylinder and the brake cylinder, a communication between the two cylinders, a valve in said communication opening towards the small cylinder, a fluid reservoir, a communication between the large cylinder and the fluid reservoir, a second valve in said communication, said second valve opening under pressure in the large cylinder, resilient return means for said second valve, and an element subjected to the pressure in the small cylinder and acting when moved under such pressure to open said second valve, said first valve, second valve and element being carried by the piston unit.

13. A fluid pressure device comprising a cylinder having a large chamber and a small chamber, a piston reciprocable in the chambers, means for by-passing fluid from the larger chamber past the piston into the small chamber, a discharge outlet for the small chamber, means for relief of pressure on the fluid in the larger chamber including a valve having a part subjected to pressure on the fluid in the large chamber and another part of smaller area than the first part subjected to pressure on the fluid in the small chamber, the combined pressures acting in the same direction on said parts and tending to open the valve, and means urging the valve to close.

14. A fluid pressure device comprising a compression cylinder having a large chamber and a small chamber, a piston unit sealing with both of said chambers, bypass valve means permitting flow of fluid from the larger to the smaller chamber, a discharge outlet for the smaller chamber, said piston unit providing a passageway connecting that part of the larger chamber in front of the piston unit with that part of the larger chamber in rear thereof, said piston unit comprising spring-pressed valve means normally closing said passageway, and means for advancing said piston unit in said chambers to create fluid pressures therein, said last-named valve means having a part acted upon by fluid pressure in the small chamber and another part of larger area than the first part acted upon by fluid pressure in the large chamber whereby said valve means opens in response to the sum of the forces, as distinguished from the difference between the forces, exerted on said parts by the fluid pressures in the large and small chambers.
